Primary Examiner—Ted Shooman*Assistant Examiner*—Nanda Bondade*Attorney, Agent, or Firm*—Gary L. Eastman, Esq.**[57] CLAIM**

The ornamental design for a vending machine with bubbling front display panel, as shown and described.

DESCRIPTION

FIG. 1 is a perspective view of a vending machine with bubbling front display panel showing our new design;

FIG. 2 is a front view thereof;

FIG. 3 is a back view thereof;

FIG. 4 is a top view thereof;

FIG. 5 is a bottom view thereof; and,

FIG. 6 is a right side view thereof.

The left side view of the vending machine with bubbling front display panel is a mirror image of FIG. 6.
